UNITED STATES PATENT OFFICE.

EARL M. McCURRY, OF COLUMBIANA, OHIO.

TIRE-CORE.

1,247,434.

Specification of Letters Patent. Patented Nov. 20, 1917.

Application filed January 15, 1917. Serial No. 142,549.

To all whom it may concern:

Be it known that I, EARL M. McCURRY, a citizen of the United States, residing at Columbiana, in the county of Columbiana 6 and State of Ohio, have invented certain new and useful Improvements in Tire-Cores: and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to improvements in tire-cores.

The invention has for its object to provide a core, which may be readily removed from a tire which has been built thereon.

20 A further object is to provide for forming the core in readily separable sections which are adapted to be effectively retained in assembled relation and whereby they may be readily disassembled as intimated.

25 A still further object is to provide for carrying out the aforesaid ends in a simple, inexpensive and expeditious manner, and with facility.

The invention consists therefore of certain 30 instrumentalities and features of construction substantially as hereinafter fully disclosed and defined by the appended claims.

In the accompanying drawings is illustrated the preferred embodiment of my invention wherein it will be understood that various changes and modifications may be made as to the detailed construction and arrangement of parts without departing from the scope of the claims, and in which draw- 35 ings:

Figure 1 is a side elevation of my invention.

Fig. 2 is a plan view thereof.

Fig. 3 is a transverse section taken 40 through a portion of the core.

Fig. 4 is also a view in side elevation thereof, with one of the core-sections, or segments, shown disassembled and relatively disposed with respect to the vacancy caused 45 by such removal.

Figs. 5, 6 and 7 are detailed fragmental views of certain elements of the core, which will be readily understood from the following description.

50 In carrying out my invention, I form or build the core, generally designated as 1,

of a plurality of sections, or segments 2, 3, 4 and 5, the whole forming a true circle, the section or segment 2, being the shortest or of the least arc, and with its ends parallel, accordingly abutting or forming joints with the adjoining sections or segments in non-radial lines as at 6, the other sections or segments having their abutting or joint-forming ends on radial lines, as at 7. This arrangement, it will be seen, provides for the ready withdrawal inwardly of section 2, whereupon the other sections or segments may be readily disjointed or displaced as called for in removing the core from the 70 tire at the end of the tire-forming operation. The core-sections or segments are enlarged at their peripheral or circumferential portions along oval or oblong lines, as at 8, for the requisite formation of the tire in the 75 molding operation. These core-sections or segments are each formed of complemental arcuate elements, suitably riveted together, as shown, and provided with arcuate laterally facing grooves practically in continuation of each other to constitute a continuous annular groove 9, which groove is adapted to receive a ring or annulus 10 for locking said sections or segments against endwise or other displacement. The resultant rings 11, 80 11^a of the arcuate elements of said segments or sections are recessed from staggered longitudinal edges, as at 12, 13 to receive correspondingly raised surfaces as 14, 15 thereof, which provide for the relatively halving 85 said rings or annuli together as indicated in Fig. 3. The meeting surfaces of the ring-forming arcuate sections or segments 2, etc., are provided with interfitting or registering 90 sockets and tenons 16, 17 respectively for 95 aiding the alinement-retention of the same, as is apparent. The ring or annulus 10, it will be observed, provides, in conjunction with the resultant angled, or one and one-half inch, joint between the arcuate sections 100 or segments 2, etc., for drawing or clamping said parts tightly in position and against any possible displacement or working loose in the use of the core; also it will be noted that the use of screws or other similar fastenings, is disposed of in the assembling or adjusting the parts, as in applying the same.

It will be understood that in the building or constructing the tire, the unvulcanized pieces or strips of textile material, as canvas and the like, are initially applied to the core by suitably winding the same thereon 105 110

in the usual way and that, after this initial part of the tire-building operation has been completed, the core, with the applied unvulcanized strips, is transferred to the vulcanizer for effecting the tire finishing operation, the core then being removed in the manner as above indicated for disassembling the respective core sections or segments, all being readily understood, as is believed appreciable from the aforesaid disclosure.

I claim:

1. A collapsible core for pneumatic tires, including a plurality of sections cut from a continuous annular member, provided with a relatively large annular chamber, a plurality of sections cut from a continuous annular member, the length of the said last mentioned sections being at variance with the length of the first mentioned sections and disposed within the said relatively large chamber in the first mentioned sections, means for securing each of the sections of the second mentioned plurality of sections to each of the first mentioned plurality of sections to produce the sections of the tire core, a tongue and slot formation in the abutting ends of the core sections, one section of each of the two plurality of sections being cut on parallel lines, the other cuts of said sections being on radial lines, a filling-in piece at the cuts of the sections to compensate for the thickness of the cuts, the sections of one of the annular members forming in connection with the sections of the other annular members an annular groove, and a continuous annular ring to enter said groove to maintain the core sections in proper and rigid relative position.

2. A collapsible core for pneumatic tires, including a plurality of sections, each section including members cut from continuous annular members, the members of each section being of different lengths in such manner that one member of one section will overlap a member of a next adjacent section, the said two members of each section being of such relative dimensions as to provide a continuous annular groove between the members of each section when the members are in an assembled position, and a continuous annular ring to enter the said continuous groove for maintaining the said sections in proper relative assembled position.

3. A collapsible core for pneumatic tires, including a plurality of sections, each section comprising two members, each of which members is cut from a continuous annular member, the members of each section being of different lengths, means for securing the members of each section together in such manner that one member of the section will overlap a member of an adjacent section when the sections of the core are in an assembled position, the two members of each section forming between each other a continuous annular groove when the core sections are in assembled position, and a continuous annular ring in the said annular groove to maintain the said core sections in proper relative position.

In testimony whereof, I affix my signature, in the presence of two witnesses.

EARL M. McCURRY.
